UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

GOVERNING MECHANISM FOR CENTRIFUGAL AIR-COMPRESSORS.

1,061,689.

Specification of Letters Patent.

Patented May 13, 1913.

Application filed October 2, 1911. Serial No. 652,284.

To all whom it may concern:

Be it known that I, RICHARD H. RICE, a citizen of the United States, residing at Lynn, in the county of Essex, State of Massachusetts, have invented certain new and useful Improvements in Governing Mechanisms for Centrifugal Air-Compressors, of which the following is a specification.

The present invention relates to governing mechanism for motor driven centrifugal air compressors and has for its object to provide a mechanism which is effective in operation and is as simple as possible consistent with the work to be performed.

In carrying out my invention a centrifugal air compressor of suitable construction is provided which is driven by an electric motor. As shown the motor is of the three phase induction type. Between the source of electric current supply and the motor is located a variable resister, preferably a water rheostat. The moving part of the rheostat is actuated by a small pneumatic motor that receives its supply of air from the said compressor. The pneumatic motor is controlled by a pilot valve and the latter is actuated by a float whose position changes with variation in the volume of air flowing through the compressor. The parts are so organized and arranged that as the flow of air through the compressor to the blast furnace or other consumptive device decreases, the float will move in a direction to cause the pneumatic motor to decrease the resistance in circuit with the electric driving motor of the compressor. As a result of this the motor and compressor increase in speed until the pressure of the air discharged by the compressor is increased to the proper value. When the resistance to the flow of air through the blast furnace decreases the float will be lifted by the increased volume of air, and the parts controlled by said float will decrease the speed of the compressor and its driving motor, thereby decreasing the air pressure. The effect of these various operations is to maintain a constant rate of flow of air through the compressor and blast furnace.

In the accompanying drawings Figure 1 is a side elevation of the compressor with the governing mechanism and rheostat, Fig.

2 is a plan view of the same, Fig. 3 is a vertical section taken through the intake of the compressor and through the water rheostat, 55 the parts being shown on a larger scale than in Figs. 1 and 2, Fig. 4 is a diagram of the electric connections, and Fig. 5 is a perspective view of the operating parts.

The compressor has a casing 1 containing 60 a suitable impeller which is not shown but which is driven by an electric motor 2 which is preferably of the induction type. The intake of the compressor is shown at 3 and the delivery pipe at 4. Located in the intake is a float 5 consisting preferably of a disk whose diameter bears a certain relation to that of the intake. The float is mounted upon a spindle 6 which is suitably guided in bearings 7 and 8, so as to be capable of longitudinal movement in the intake 3. The upper end of the spindle 6 is pivotally connected to a floating lever 9 which is fulcrumed in the upper end of a piston rod 10 attached to a movable abutment such as the piston 11 operating in a cylinder 12 and constituting a motor for varying the distance between the movable electrodes in the water rheostat hereinafter described. The opposite end of the lever 9 is connected by a rod 13 to the movable portion of a dash-pot 14 and this end of the lever also is provided with an adjustable weight or counter-balance 15. Attached to the piston rod 10 at the point where the lever 9 is fulcrumed to it 85 is a cross-head 16, which carries two levers 17 each provided with an adjustable counter-weight 18. Said levers are fulcrumed on a cross-bar 19 supported in a bracket 20 which is preferably attached to the walls of the 90 water rheostat. Fulcrumed on the same cross-bar 19 are two lever arms 21 which have short ends carrying lugs 22 that lie underneath the levers 17. The opposite ends of said lever arms 21 are hooked in order to 95 engage with a cross-bar from which the movable electrode or electrodes of the water rheostat can be suspended. I prefer to use three such electrodes 23 mounted at the lower ends of rods 24 depending from the 100 cross-bar 25 with which the levers 21 engage. The stationary electrodes 26 are located at the bottom of the water rheostat in line with the movable electrodes 23. The lower por-

tion of the vessel or receptacle 27 constituting the water rheostat is inclosed in a protecting jacket 28 which is provided with perforations to permit of a free circulation of air for the purpose of cooling this portion of the rheostat. The upper portion of the receptacle 27 is preferably somewhat larger than the lower portion in order to enable it to receive a coil of pipe 29 through which a cooling medium can be circulated in order to carry off the heat arising from the passage of the current between the electrodes 23 and 26. The minimum distance between the electrodes can be adjusted in any suitable manner, preferably by means of a U shaped stop member 30 projecting from a nut 31 which meshes with an upright screw 32 journaled in bearings in a frame 33 secured to the receptacle 27. This screw is rotated by a hand-wheel 34 which is preferably connected therewith by bevel gearing 35. A small pipe 36 conveys air pressure from the delivery pipe 4 of the air compressor to a valve chest 37, in which is located a small pilot valve 38, controlling admission and exhaust ports which lead to the cylinder 12. The stem 39 of said valve is pivoted to the lever 9. The operation of the device is as follows:—Assuming the compressor to be operating and driven by the induction motor 2, if now a choking condition occurs in the blast furnace it will lessen the volume of air passing through the compressor. Consequently the float 5 which is responsive to changes in volume will drop, say to the position indicated by the dotted lines in Fig. 3. The downward movement of the spindle 6 depresses the lever 9 to the position shown in dotted lines thereby pushing down the stem of the pilot valve 38 and admitting compressed air through the pipe 36 to the lower part of the cylinder 12. The piston 11 is forced upward carrying with it the cross-head 16 and the levers 17 to the position shown in dotted lines in Fig. 3. Incidentally this lifts the stem of the pilot valve until the valve is restored to its mid-position thereby retaining the piston in its elevated position. The lifting of the levers 17 releases the two lever-arms 21, and the weight of the electrodes 23 and their rods 24 causes said lever-arms to fall to the dotted line position thereby allowing the movable electrodes to approach the lower stationary electrodes. This action reduces the resistance of the rotor circuit of the motor 2 in which circuit the water rheostat is included, thereby causing said motor to speed up and drive the air compressor at a higher velocity. The increased pressure of the air current and its greater volume per unit of time compensates for the obstruction to the flow and maintains the output of the blast furnace.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,

1. The combination with an air compressor, of a motor for driving it, a regulator for the motor having a movable member, a float arranged in the stream of air passing through the compressor, a floating lever, a rod connecting the float to the lever, a fluid motor having a movable member, a pilot valve for the fluid motor having a stem connected to the floating lever, a connection between the movable member of the fluid motor and the floating lever, lever means for controlling the movable member of the regulator and comprising lever arms connected to said movable member, other lever arms pivoted on the same axis as the first arms but movable independently thereof in one direction, a connection between said means and the floating lever, and means for limiting the movement of the movable member of the regulator in one direction.

2. The combination with an air compressor, of a motor for driving it, a regulator for the motor having a movable member, a float located in the stream of air passing through the compressor, a floating lever, a rod connecting the float to the lever, a fluid motor having a movable member, a pilot valve for the fluid motor having a stem connected to the floating lever, a connection between the movable member of the fluid motor and the floating lever, a cross-head connected to the floating lever adjacent to the last connection, levers pivoted adjacent to the cross-head and connected thereto, other levers pivoted on the same axis as the first levers and connected thereto, said sets of levers being movable independently of each other to a limited extent, and means connecting the last named levers to the movable member of the regulator.

3. The combination with an air compressor, of a motor for driving it, a regulator for the motor having a movable member, a float in the intake of the compressor, a floating lever, a rod that extends through the wall of the intake and connects the float to the lever intermediate its ends, an adjustable counterweight on one end of the lever, a dash-pot connected to said end of the lever, a fluid actuated motor having its piston and pilot valve connected to the lever adjacent the other end, a cross-head connected to said other end, levers pivoted adjacent to said end of the floating lever, extending in the direction of said lever and

connected to the cross-head, and other levers pivoted on the same axis as the first levers and extending away from the floating lever, there being lugs on the last named 5. levers that engage the arms of the first levers to cause said sets of levers to move together under certain conditions and also to permit movement of the first levers inde-

pendently of the second under other conditions.

In witness whereof, I have hereunto set my hand this 25th day of September 1911.
